UNITED STATES PATENT OFFICE

MICHAEL B. BOWEN, OF DECATUR, ILLINOIS, ASSIGNOR TO FARIES MANUFACTURING COMPANY, OF DECATUR, ILLINOIS, A CORPORATION OF ILLINOIS

SHADE HOLDER FOR PORTABLE ELECTRIC LAMPS

Application filed August 20, 1929. Serial No. 387,192.

My invention relates to that class of shade holders employed in portable desk lamps such as are described in United States Letters Patent No. 1,225,051, issued May 8, 1917, in which the shade which encloses the illuminating element is slidably mounted upon a plate depending from the arm on the standard.

These plates were cast metal, having V-shaped grooves machined in their edges. The machining of these grooves is an expensive operation, and in addition to the expense, the shade is left free to slide easily, with the result that frequently, in moving the lamp, the shade drops off and is broken.

My invention has for its object, to provide a simple means for forming this plate out of a stamping, and at the same time provide means which will effectually prevent the shade being dislodged accidentally, though permitting its comparatively easy removal from the holder.

My means for accomplishing the foregoing object may be more easily understood by reference to the accompanying drawings, which are hereto annexed and are a part of this specification, in which—

Fig. 1 is a plan view of the blank from which my improved plate is formed;

Fig. 2 is a vertical section on the line 2—2 in Fig. 1;

Fig. 3 is a front elevation of the plate formed from the blank shown in Fig. 1;

Fig. 4 is a cross section on the line 4—4 in Fig. 3, the securing means being shown in dotted lines;

Fig. 5 is a cross section on the line 5—5 in Fig. 3; and

Fig. 6 is a rear elevation of a shade holder provided with tongues or guides fitted to the V-shaped groove of the plate.

Similar reference numerals refer to similar parts throughout the entire description.

As shown in the drawings, a blank 1 is stamped as shown in Fig. 1, the edges 2 thereof being beveled, as clearly shown in Fig. 2. Apertures 3 are formed in the blank 1, and protuberances 4 are punched out of the metal on the bevel 2. The blank 1 is then bent into the shape shown by Fig. 3. This brings the

apertures 3 in register with each other, and the protuberances 4 opposite to each other projecting into the V-shaped groove 9 formed by the bending of the blank 1 upon itself, as clearly seen in Figs. 3 and 4.

A shade holder 10, formed in accordance with the holder described in my copending application, Serial No. 387,189, filed August 20, 1929, comprises a pair of plates 5 (only the rear plate being shown herein), which are fastened together by screws 6. These plates 5 are formed with central arch-like openings, the vertical edges of which are provided with V-shaped tongues or guides 8, which are fitted to and coincide with the V-shaped groove 9, as clearly seen on Figs. 5 and 6. Recesses 11 are formed in the V-shaped tongues or guides 8, adapted to receive the protuberances 4 formed on the bevel 2 of the blanked plate 1.

The result of this construction is obvious. When the shade holder 5 is placed upon the plate formed from the blank 1, the V-shaped tongues or guides 8 register with the V-shaped groove 9 in the plate 1, and as the plate 1 slides into the holder 5, the protuberances 4 on the bevel 2 of plate 1 enter the recesses 11 formed in the V-shaped tongues or guides 8, and the holder is secured against accidental dislodgment.

It will be apparent from the foregoing description that by this construction the supporting plate 1 is formed entirely of sheet metal, which is stamped and therefore requires no machine work thereupon, thus materially reducing the cost of manufacture.

Having described my invention, what I regard as new, and desire to secure by Letters Patent of the United States, is:

1. A device of the character described, comprising a metal plate, having a peripheral bevel formed thereon, the edges of said plate, when folded back upon itself, forming a V-shaped groove, protuberances formed on said bevel, which correspond in position when said plate is folded, a shade holder, V-shaped guides thereon, which coincide with said V-shaped groove, there being recesses in said guides which register with the protuberances

on the bevels when said shade holder is in position.

5 2. A device of the character described, comprising a metal plate, having a peripheral bevel formed thereon, the edges of said plate, when folded back upon itself, forming a V-shaped groove, and protuberances formed on said bevel which correspond in position when said plate is folded.

10 3. A device of the character described, comprising a metal plate having a V-shaped groove formed thereon, a shade holder having V-shaped guides thereon, and means on said V-shaped guides to prevent accidental 15 disengagement from said V-shaped groove.

20 4. A device of the character described, comprising a metal plate, having a peripheral bevel formed thereon, the edges of said plate, when folded back upon itself, forming a V-shaped groove, recesses formed in said bevel, which correspond in position when said plate is folded, a shade holder, V-shaped guides thereon, which coincide with said V-shaped groove, there being protuberances 25 on said guides which register with the recesses in the bevels when said shade holder is in position.

MICHAEL B. BOWEN.
